Description

Development history

The Eisenhower dollar was a one-dollar coin issued by the United States Mint from 1971 to 1978; it was the first coin of that denomination issued by the Mint since the Peace dollar series ended in 1935. The coin depicts President Dwight D. Eisenhower on the obverse, and on...

Coin design

For Mint Chief Engraver Frank Gasparro, the opportunity to put Eisenhower on a coin was the fulfillment of a longtime dream. On June 19, 1945, Gasparro had been one of more than 4 million people who gathered in New York to watch a parade celebrating the Allied victory in...
